Filed July 2, 1965, Ser. No. 86,003

Term of patent 14 years

(Cl. D14—3)

FIG.1

FIG.2

FIG.3

FIG.4

FIG. 1 is a top plan view of a self-propelled vehicle, showing my new design;

FIG. 2 is a view of the left-hand side of the self-propelled vehicle shown in FIG. 1;

FIG. 3 is a view of the opposite side thereof; and

FIG. 4 is a cross-sectional view partly in end elevation, looking from one end of the self-propelled vehicle toward the front of the vehicle.

The dominant features of my new design are shown in solid lines in the drawing.

I claim:

The ornamental design for a self-propelled vehicle, substantially as shown and described.
